(57) **CLAIM**

The ornamental design for a carrier for floral arrangements and plants, as shown and described.

DESCRIPTION

FIG. 1 is a front perspective view of a carrier for floral arrangements and plants in accordance with the subject disclosure.

FIG. 2 is a bottom perspective view thereof;

FIG. 3 is a front perspective view showing the environmental structure of a small base of a pot in broken line, thereof; FIG. 4 is a front perspective view showing the environmental structure of a large base of a pot in broken line, thereof; FIG. 5 is a left-side view, the right side being a mirror image, the front being an identical image, the rear view being a mirror image, thereof;

FIG. 6 is a right side, cross sectional view taken along line "A-A" in FIG. 5, thereof;

FIG. 7 is a top view thereof; and,

FIG. 8 is a bottom view thereof.

The broken lines showing a pot base in FIGS. 3 and 4 are included for the purpose of illustrating environmental structure and form no part of the claimed design.

1 Claim, 8 Drawing Sheets
